UNITED STATES PATENT OFFICE

MARTIN S. BENTLEY, OF ST. HELENA, CALIFORNIA

STROP HOLDER

Application filed June 11, 1928. Serial No. 284,614.

This invention relates to improvements in strop holders.

The principal object of this invention is to provide a strop holder wherein the strop is prevented from rotating in one direction only.

A further object is to produce a device of the character which may be attached to any ordinary strop now upon the market without 10 altering the construction of the same.

A further object is to produce a device which is economical to manufacture, one which is strong and at the same time neat in appearance.

15 A still further object is to produce a holder which may be attached to either the wall or underside of a chair, as for instance, a barber's chair.

Other objects and advantages will be apparent during the course of the following description.

In the accompanying drawing forming a part of this specification and in which like numerals are employed to designate like parts 25 throughout the same,

Figure 1 is a top plan view of my device as the same would appear when attached to the wall and having a portion of the strop secured thereto,

20 Figure 2 is a side elevation of Figure 1, Figure 3 is a cross section taken on the line 3—3 of Figure 1, and

Figure 4 is a top plan view of the locking washer.

25 At the present time a strop is usually provided with a swivel at one end thereof which swivel permits the strop to accommodate itself to the angle to which the razor being stropped, is held. It often occurs that the 30 razor will slip off the strop and upon the return movement of the hand to bring the razor back to the strop, the razor will engage the strop in such a manner as to cause it to turn and consequently be cut upon the 35 next stroke. Many a strop has been ruined in this manner.

Applicant has therefore provided a device which will prevent such occurrences.

In the accompanying drawings wherein 40 for the purpose of illustration is shown a

preferred embodiment of my invention, the numeral 5 designates a supporting surface such as a wall or the arm of a barber's chair. To this supporting surface is attached a bracket 6 which is provided with arms 7 and 8. A similar bracket is shown at 9, which is provided with arms 11 and 12. A pivot pin is shown at 13 which pivot pin passes through the arms 7, 11, 12 and 8, thereby permitting the bracket 9 to rotate with respect to the bracket 6. The bracket 9 has an opening therethrough which permits a stud 14 to extend through the bracket as illustrated in Figure 1. This stud is provided with a head 16 which has a squared undersurface adapted to engage a squared opening in a washer 17. This washer is provided with notches as shown at 18 and 19 which notches are adapted to be alternatively engaged by a pivot latch 21, pivoted as at 22 to the bracket 9 and having its free end in engagement with the washer by a spring 23. The stud 14 is held in contact with the washer 16 through the medium of a spring 24, which spring is held upon the stud by a pivot pin 26. This pivot pin 70 also forms a means for securing a strop holding clamp 27.

The strop is shown at 28 and secured in the clamp 27 as by a screw 29. Assuming that a strop has been secured to my device and that the device has been attached to a support, the user grasps the end of the strop in the left hand and strops the razor in the usual manner. It will be noted however, that the tendency of the strop to rotate in a clockwise 85 direction is prevented by the latch 21.

If the operator wishes to turn the strop over so as to use the canvas side, he turns the strop in a counter clockwise direction and then proceeds to apply the razor thereto. Should the operator be left handed, there is but a moment's work to reverse the position of the washer 16 which of course will prevent the strop from rotating in a counter clockwise direction and will therefore accommodate a left handed person.

It is to be understood that the form of my invention herewith shown and described is to be taken as a preferred example of the same and that various changes relative to the ma-

terial, size, shape and arrangement of parts may be resorted to without departing from the spirit of the invention or the scope of the subjoined claim.

5 Having thus described my invention, I claim:—

In a device of the character described, a pair of brackets pivoted one to the other, a stud extending through one of said brackets, 10 said stud having a squared portion formed thereon, a washer positioned on said stud and engaging the squared portion thereof, said washer having notches formed in the periphery thereof, a latch pivotally secured to said bracket and adapted to engage said washer 15 for the purpose of preventing rotation of said washer in one direction only, a strop securing clamp secured to said stud and a spring interposed between said bracket and said 20 strop securing clamp.

In testimony whereof I affix my signature.
MARTIN S. BENTLEY.
